UNITED STATES PATENT OFFICE.

BURLEIGH A. TRAVIS, OF CAPE CHARLES, VIRGINIA.

DESIGN FOR A BACKBAND HOLDER.

Application filed August 9, 1920. Serial No. 402,445. Term of patent 14 years.

To all whom it may concern:

Be it known that I, BURLEIGH A. TRAVIS, a citizen of the United States, residing at Cape Charles, in the county of Northhampton and State of Virginia, have invented a new, original, and ornamental Design for Backband Holder, of which the following is a specification, reference being had to the accompanying drawings, forming a part hereof.

I claim:

The ornamental design for a backband holder as shown.

BURLEIGH A. TRAVIS.

Witnesses:

BENNETT S. JONES,
J. SCHMID KING.
